MINE VEIN-ATTACKING AND DISINTEGRATING MECHANISM HAVING A HEAD FRAME WITH AN ADJUSTABLE OUTER END PORTION

John R. Sibley, Franklin, Pa., assignor to Joy Manufacturing Company, Pittsburgh, Pa., a corporation of Pennsylvania

Original application July 5, 1949, Serial No. 102,996, now Patent No. 2,798,713, dated July 9, 1957. Divided and this application June 16, 1955, Serial No. 515,968

3 Claims. (Cl. 262—28)

This invention relates to a continuous mining apparatus and more particularly to guiding and adjusting means for the adjustable head frame of a continuous miner.

In a continuous mining apparatus of the kind disclosed in my copending application Serial No. 102,996, filed July 5, 1949, now Patent No. 2,798,713, a vein-attacking and disintegrating mechanism is swingable in vertical planes for dislodging and disintegrating the mineral of a solid mine vein. In such an apparatus, the attacking and disintegrating mechanism has a swingable head frame about which a series of endless disintegrating chains are guided for orbital circulation and the outer end portion of the head frame is adjustable to provide for proper tensioning of the disintegrating chains. The present invention contemplates improvements in such mining apparatus in that the adjustable outer end portion of the swingable head frame is guided and adjusted in an improved manner.

An object of the present invention is to provide an improved mine vein-attacking and disintegrating mechanism. Another object is to provide an improved guiding and adjusting means for the adjustable outer end portion of the head frame of the attacking and disintegrating mechanism. These and other objects and advantages of the invention will, however, hereinafter more fully appear.

This application is a division of my copending application Serial No. 102,996, filed July 5, 1949, which is a continuation-in-part of application Serial No. 47,422, filed September 2, 1948, now abandoned.

In the accompanying drawings there is shown for purposes of illustration one form which the invention may assume in practice.

In these drawings:

Fig. 1 is a longitudinal vertical sectional view taken through the forward portion of a continuous mining apparatus and illustrating details of the improved guiding and adjusting means for the disintegrating head frame.

Fig. 2 is an enlarged cross section taken on line 2—2 of Fig. 1.

Fig. 3 is a transverse horizontal section taken on line 3—3 of Fig. 1.

Fig. 4 is a fragmentary side elevational view of the vein-attacking and disintegrating mechanism.

The continuous mining apparatus of the present invention generally comprises a base 1 carrying a frame structure 2 on which a mine vein-attacking and disintegrating mechanism or so-called disintegrating head generally designated 3 is pivotally mounted at 4 to swing in vertical planes. Associated with the attacking and disintegrating mechanism is a floor clean-up device 5 carried by the frame structure 2 beneath the attacking and disintegrating mechanism. Extensible fluid jacks 5' operatively connected to depending armlike projections 6 secured to the head frame serve to swing the attacking and disintegrating mechanism in vertical planes about its

2

pivot during the mining operation, and a conveyor means 7 on the frame structure receives the disintegrated mineral discharged from the attacking and disintegrating mechanism and conveys the mineral received thereby rearwardly of the apparatus.

The attacking and disintegrating mechanism 3 comprises a vertically swingable head frame or bar structure 8 extending forwardly in advance of the frame structure 2. A series of endless disintegrating chains 9 are guided in parallel guideways 10 for circulation in vertical orbital paths about the head frame and each chain comprises a series of chain blocks 11 pivotally connected by strap links 12 which are pivotally connected to the blocks by hinge pins 13. The blocks have lateral gibs 14 at their bases received in the guideways, and projecting laterally in the blocks are lugs 15 which have sockets for receiving disintegrating elements, preferably in the form of conventional cutter bits 16 held in position on the lugs by conventional set screws 17. The frame or bar structure 8 has an adjustable outer end portion or bar idler head 19 having side frame portions or plates 20 provided with rearward guides 21 received in longitudinal guiding slots 22 in the sides of the rearward side plates 28. The guides 21 have longitudinal slots 23 which are engaged by retaining blocks 24 secured to the forward ends of the side plates 28. In this improved construction, the adjustable front end portion has parallel tubular elements 25 secured to the adjustable outer end portion 19 and slidably received in parallel longitudinal tubular guides 26 secured to transverse plates 27 which rigidly brace the forward ends of the side plates 28 of the rearward frame portion. The tubular guides 26 are preferably welded to the transverse plates 27 and have parallel bores in which the tubular elements 25 are received. The tubular elements have threaded portions 29 engaged by adjusting screws 30, and the screws have collars 31 engaging inwardly directed flanges 32 on the rearward ends of the tubular guides 26. The screws have polygonal portions 33 which are accessible through suitable side openings 34 in the side plates 28 and are engageable by a suitable turning instrument such as a wrench.

Supported within end supports 35 secured to the side plates 20 of the bar idler head is a transverse shaft 36 which supports bearings 37 on which an elongated idler roll 38 is journaled. The endless disintegrating chains are guided by the idler roll 38 as they pass around the outer end of the swingable bar structure 8. Thus, by suitably adjusting the screws 30, the adjustable frame portion or bar idler head 19 may be adjusted longitudinally outwardly or be permitted to move longitudinally inwardly along its guides relative to the rear frame portion to vary the tension of the chains.

The motor operated driving means for the disintegrating chains, as disclosed in my copending application above referred to, includes a transverse drive shaft 39 coaxial with the pivot of the swingable frame 8, and keyed to this shaft is a series of chain sprockets 40 which engage and drive the endless disintegrating chains.

As a result of this invention, an improved mine vein-attacking and disintegrating mechanism is provided having improved adjusting means for the disintegrating elements. By the provision of the improved guiding and adjusting means for the outer end portion of the disintegrating head, adjustment of the endless disintegrating chains may be readily and easily effected. The improved structure is relatively compact, readily accessible, and simple and rugged in design. Other advantages of the invention will be clearly apparent to those skilled in the art.

While there is in this application specifically described one form which the invention may assume in practice, it

will be understood that this form of the same is shown for purposes of illustration and that the invention may be modified and embodied in various other forms without departing from its spirit or the scope of the appended claims.

What I claim as new and desire to secure by Letters Patent is:

1. In an endless chain mechanism, a frame means having a chain sprocket driving means at one end, a chain guide head mounted at the other end of said frame means, chain guide head mounting means including concentric inner and outer tubular elements fixed to respectively said chain guide head and said frame means, said guide head mounting means also including frame side and chain guide head side plates, a frame side plate groove, a chain guide head side plate projection, said projection slidably received in said groove, a slot in said chain guide head side plate projection longitudinally extended along the projection, a block mounted to the base of said side plate groove through said slot holding said projection in said groove, relative motion between said chain guide head side plate projection and said frame side plate limited to motion of the projection longitudinally along the axis of said groove, relative motion between said inner and outer tubular elements limited to a longitudinal axis parallel to the axis of permissible motion of said chain guide head side plate projection in said frame side plate groove.

2. In the endless chain mechanism of claim 1, endless chain tension adjusting means comprising force exerting means between said inner and outer tubular elements which positively increases and permits a decrease in the outward position of said chain guide head relative to said frame means and of the inner tubular element in the outer tubular element and respectively increasing and decreasing tension in the endless chain.

3. In a spacing and endless chain tension adjustment means between a first and second relatively movable frame elements having guideways for an endless chain, concentric relatively movable inner and outer tubular

elements, means for maintaining rotational alignment between said first and second relatively movable frame elements, said outer tubular element longitudinally fixed to said first frame element, said inner tubular element longitudinally and rotationally fixed to said second frame element, said inner and outer tubular elements having coating guide elements for spacing and tension adjustment of said second frame element longitudinally along the axis of said tubular elements, a screw adjusting means cooperatively threaded to said inner tubular element, a thrust face at one end of said screw adjusting means, a thrust abutment on said outer tubular element, said thrust abutment providing an abutment for the thrust face of said screw adjusting means, an opening through said thrust abutment, and adjusting means on the screw adjusting means thrust face adapted for suitable tool engagement in the region of said opening, said means for maintaining rotational alignment between said first and second relatively movable chain guiding frame elements comprising a first side plate with a longitudinal guiding slot fixed to said first frame element, a second side plate with a guide projection slidably received in said longitudinal guiding slot of said first side plate, the said second side plate fixed to said second frame element, a block mounted on the inner wall of the guiding slot of said first side plate, and a slot within and longitudinally aligned with said guide projection, said block engaged in said last mentioned slot for retaining said guide projection of said second side plate in the slot of said first side plate.
